UNITED STATES PATENT OFFICE.

WILLIAM GAUGHRIN, OF CHICAGO, ILLINOIS.

CLINKER-REMOVING DEVICE.

Application filed February 12, 1926. Serial No. 87,816.

My invention relates to furnaces and has for its object the provision of mechanism for removing clinkers from the walls thereof.

The mechanism of my invention includes 5 a clinker removing member, preferably in the form of a knife, a carrier for this member adapted to be placed next a wall of a furnace in the zone of the clinkers and mechanism for causing the carrier to travel, the 10 clinker removing member contacting with the clinkers at their bases and removing the same in its travel. The carrier for the clinker removing member is preferably in the form of a horizontal endless conveyor, 15 such as a chain, this conveyor having a suitable support for locating it in such relation to the selected wall of a furnace that the clinker removing member on the conveyor will discharge the clinkers as the 20 clinker removing member travels with the conveyor.

Where my invention is employed in connection with a furnace having an endless traveling chain grate, I desirably employ 25 two clinker removing members that are provided upon the grate respectively adjacent its opposite sides and in position to contact with the base portions of the clinkers as the grate travels in the operation of the furnace. 30 These clinker removing members, preferably in the form of knives, as stated, are desirably so assembled with the chain grate that they will fall from the grate as the grate rounds the inner orbit of its travel, the 35 clinker removing members being thus prevented from having violent contact with any of the lower stationary portions of the grate structure or furnace.

The invention will be more fully explained in connection with the accompanying drawing in which Fig. 1 is a side elevation of the preferred embodiment of my invention as employed in connection with an endless chain grate, a portion of the 40 furnace and its grate being broken away due to lack of space; Fig. 2 is a sectional plan view on line 2-2 of Fig. 1; Fig. 3 is a sectional view of a part of the structure on line 3-3 of Fig. 2; Fig. 4 is a sectional view of a link in the grate chain, taken on line 4-4 of Fig. 5; and Fig. 5 is a side view of a chain link, shown partially in section, with the clinker removing knife 45 assembled therewith.

The invention is applicable to furnaces of various types. The furnace shown has

upright side walls 1, a back wall 2 and a bottom wall 3, the latter wall being, for example, level with the floor of the furnace room. The grate structure of the furnace 60 includes an endless chain formed of links 4 which are suitably connected abreast and in tandem, to constitute an endless conveyor for the fuel discharged upon the upper stretch of the chain through a hopper 5 or 65 in any other manner placed upon the grate. The endless chain grate travels in an orbit defined by two drums 6 and 7 which are shaped to conform to the chain that encloses them. These drums have horizontal axes 70 of rotation, the inner drum 7 being provided upon a shaft 8 which is journaled in adjustable blocks 9 that are movable horizontally between guides 10. The outer drum 6 is mounted upon a shaft 11 upon 75 which is fixed a worm gear 12. This worm gear is turned by a worm 13 which is in mesh therewith and which, itself, is turned by any suitable means such as an electric motor 14. A truck frame carries the afore- 80 said drums and the bearings therefor, this truck frame being inclusive of two upright side plates 15 and 16 which are assembled and held spaced apart as by means of the circular rods 17 and 18. The rods 17 are 85 located beneath the upper stretch of the chain, rollers 19 being journaled upon these rods to engage the upper stretch of the chain to prevent it from sagging. The rods 18 are located beneath the lower stretch of 90 the chain, rollers 20 being journaled upon these rods to engage the lower stretch of the chain to prevent it from sagging. Truck wheels 21 are provided upon shafts 22 that turn within bearings provided at the bottoms of the plates 15 and 16. These wheels are located on tracks 23 that extend from a suitable distance in front of the furnace to a suitable distance within the furnace to enable the grate structure and its operating 100 mechanism to be pulled out of the furnace and pushed into the furnace.

The clinker removing members, provided in accordance with my invention, are desirably in the form of steel knives having 105 bodies 24 and 25 which are right angular in shape. Each of these bodies carries pins 26 projecting from one of its sides, these pins having tapering heads upon their outer ends. One link at each side of the chain is 110 formed with key hole slots 27 in its outermost horizontal side. When the clinker re-

moving members are to be moved with the chain grate, these pins are inserted through the larger and inner ends of the key hole slots and are then moved into the smaller 5 ends of these slots, the heads of the pins being large enough to prevent them from passing through the smaller ends of said slots. One side of each clinker removing member, the side which carries the pins 26, 10 is thus placed horizontally upon the particular link 4 carrying it and the other side of this member projects upwardly and is closely adjacent the continuous furnace side wall 1. Whenever clinkers are to be removed, 15 the clinker removing members are assembled as illustrated with the chain grate links that are to carry them while these links are near the outer drum 6, the grate being, of course, then at rest. It being assumed that the 20 grate is in its functioning position, it is started to travel in its normal direction in which the upper stretch of the chain moves rearwardly, such travel being effected by the motor which drives the worm 13 that 25 turns the gear 12 and the drum 6 that is in fixed connection with this gear. The clinkers form above the top stretch of the grate chain, the clinker removing members traveling in the zone of the clinkers. The 30 clinker removing members are in the nature of knives, being formed with cutting edges 28. As the chain is caused to travel in its normal direction, these knives, whose cutting edges are parallel with and close to the 35 side walls of the furnace, will engage the clinkers at their base portions and remove them. The clinkers will lodge upon the grate and will be deposited at the rear end thereof upon the furnace floor. When the 40 links 4 which carry the clinker removing knives have been turned by the inner drum 7 to a sufficient extent, the knives will slide upon these links to bring the pins 26 into the larger portions of the key hole slots 45 27 formed in the links. When the grate chain moves sufficiently further, the clinker removing knives will fall away from the grate chain onto the furnace floor whereby 50 they are prevented from coming into engagement with the grate supporting rollers 20 upon the furnace structure or into engagement with any other part of the grate structure. The larger ends of the key hole slots are desirably counter-sunk, as illustrated in Fig. 5, so that the heads of the 55 pins will not be caught as the clinker removing knives move away, by gravity, from the chain grate.

Changes may be made without departing 60 from the invention.

Having thus described my invention, I claim:

1. Apparatus for removing clinkers from

the side walls of furnaces including an endless traveling conveyor having upper and 65 lower stretches and a clinker removing member upon said conveyor, the conveyor and clinker removing member having interengaging holding formations interacting to prevent separation of said conveyor and member when said member is in the upper 70 stretch of the conveyor to enable said member to effect removal of clinker and permitting said member to fall from the conveyor upon reversal in the direction of travel of 75 the holding formation upon the conveyor.

2. Apparatus for removing clinkers from the side walls of furnaces including an endless traveling conveyor having upper and lower stretches and a clinker removing member upon said conveyor in the form of a knife having its body portion secured to the conveyor and a clinker cutting edge portion, the conveyor and clinker removing member having interengaging holding formations interacting to prevent separation of said conveyor and member when said member is in the upper stretch of the conveyor to enable 80 said member to effect removal of clinker and permitting said member to fall from the conveyor upon reversal in the direction of travel of 85 the holding formation upon the conveyor.

3. Apparatus for removing clinkers from the side walls of furnaces including an endless traveling conveyor having upper and lower stretches and a clinker removing member upon said conveyor, the conveyor and clinker removing member having pin and key hole slot holding formations interacting to prevent separation of said conveyor and member when said member is in the upper stretch of the conveyor to enable said member to effect removal of clinkers and permitting said member to fall from the conveyor upon reversal in the direction of travel of 90 the holding formation upon the conveyor.

4. Apparatus for removing clinkers from the side walls of furnaces including an endless traveling conveyor having upper and lower stretches and a clinker removing member upon said conveyor in the form of a knife having its body portion secured to the conveyor and a clinker cutting edge portion, the conveyor and clinker removing member having pin and key hole slot holding formations interacting to prevent separation of said conveyor and member when said member is in the upper stretch of the conveyor to enable said member to effect removal of clinker and permitting said member to fall from the conveyor upon reversal in the direction of travel of 95 the holding formation upon the conveyor.

In witness whereof, I hereunto subscribe my name.

WILLIAM GAUGHRIN.
